SPACING JIG FOR CABLES TO BE ENCASED
IN CONCRETE OR THE LIKE

Charles H. Powell, 4814 1/4 W. 98th St.,
Inglewood, Calif. 90301

Filed Dec. 11, 1967, Ser. No. 9,737

Term of patent 14 years

Int. Cl. D8—02; D25—05

U.S. Cl. D8—228

FIG. 1 is a front view of a spacing jig for cables to be encased in concrete, showing my new design;

FIG. 2 is a top plan view thereof; and

FIG. 3 is a side view thereof, partially in section, taken on the broken line III—III of FIG. 2.

I claim:

The ornamental design for a spacing jig for cables to be encased in concrete or the like, substantially as shown.
